SWIVEL CONNECTOR FOR JOINING ENDS OF CHAINS OR THE LIKE

Walter Ronald Draper and Thomas Alfred Poulton,
Stourport-on-Severn, England, assignors to Parson
Chain Company Limited, Stourport-on-Severn, England

Filed Aug. 5, 1971, Ser. No. 169,589

Term of patent 14 years

Int. Cl. D8—08

U.S. Cl. D8—252

Fig. 1.

Fig. 2.

Fig.3.

FIG. 1 is an elevational view of a swivel connector for joining ends of chains or the like;

FIG. 2 is a side elevational view thereof; and

FIG. 3 is an end view thereof, both ends being the same.

We claim:

The ornamental design for a swivel connector for joining ends of chains or the like, substantially as shown and described.
